UNITED STATES PATENT OFFICE.

ADOLPH W. KEMPNER, OF NEW YORK, N. Y.

REGISTER.

1,110,942.

Specification of Letters Patent. Patented Sept. 15, 1914.

Application filed October 24, 1913. Serial No. 797,052.

To all whom it may concern:

Be it known that I, ADOLPH W. KEMPNER, a citizen of the United States, and a resident of the city of New York, borough of Manhattan, in the county and State of New York, have invented a new and Improved Register, of which the following is a full, clear, and exact description.

This invention has special reference to improvements in registers and more particularly to a device which may be termed a golfometer for keeping a count of the number of strokes for each hole and the grand total of strokes for the entire course in playing golf, and also for determining which golf hole is being played.

Another object of the invention is to provide a hand operated register designed to be suitably suspended, as from a belt or pocket, or to be fitted in the pocket, and designed to be conveniently operated, whereby a casing corresponding in size and appearance to a modern sized watch may, by means of suitable mechanism controlled by an operating stem, be so set as to permit the player to ascertain at any time during the play which golf hole is being played and the total number of strokes made for each hole, and also the grand total of strokes for the entire course, thus obviating disputes among players.

With the above and other objects in view, the invention resides more particularly in the peculiar combination and arrangement of parts which will be illustrated as a preferred embodiment in the accompanying drawings and described in the specification.

Reference is to be had to the accompanying drawings forming a part of this specification, in which similar characters of reference indicate corresponding parts in all the views, and in which—

Figure 1 is a face view of a register illustrating the principle of the invention carried out in one form; Fig. 2 is a vertical sectional view taken on the line 2—2 of Fig. 1; Fig. 3 is a plan view of a fragmentary portion of the casing of the register with the stem in section and showing means for holding the stem in different adjusted positions circumferentially of the casing; Fig. 4 is a

sectional view taken on the line 4—4 of Fig. 2; Fig. 5 is a plan view of one of the cylinders employed with the device for counting the number of strokes made for each hole; 55 and Fig. 6 is a side elevation thereof together with a beveled projection of the stem adapted to coöperate with the beveled teeth of the cylinder for partially rotating the latter, the projection being shown in section. 60

It is common at present to use a tablet and pencil to record the number of strokes employed in advancing the ball for each hole of the course in playing golf, the course varying from nine to eighteen holes, generally. 65 In the use of such method of keeping the record of the number of strokes for each hole, the particular hole being played and the total number of strokes for the entire course, through forgetfulness or otherwise 70 the record will become erroneous and misleading, thus often causing disputes among the players. The present invention is designed to overcome these objections, and in the illustrated embodiment comprises a casing about the size of a modern watch or otherwise, such casing being made up of a face or front wall 10 and a back wall 11 having inwardly extending peripheral flanges or edge walls 12 and 13, respectively. The 80 walls are held in fixed spaced relation as by means of a connecting pin or rivet 14, the walls being thickened at the points where this rivet is passed therethrough, and a sleeve 15 being tightly mounted upon the 85 rivet to hold the walls in such relation, while the rivet is further provided with a spacing flange 16 coöoperating with a flange 17 of the sleeve to form an annular groove to accommodate the sleeve portion of a bevelled pinion 18 which is relatively tightly 90 fitted upon the spacing and bearing sleeve 15. The flange 17 also coöperates with the back wall 11 to form an annular groove accommodating a bearing sleeve 19 supporting 95 the stem of the register, said sleeve being loosely mounted upon the bearing sleeve 15 so as to freely turn thereon.

The stem is indicated by the numeral 20 and is provided with a knurled head 21 by 100 which it may be turned or otherwise manipulated. The stem operates through a sleeve

22 and is provided at its inner portion with a peripheral groove 23 engaged by a set screw or pin 24 extending through the enlarged upper end of the sleeve 22 so as to permit rotation of the stem independently of the sleeve but to cause the sleeve to be shifted longitudinally with the stem. The sleeve 22 is in turn slidably engaged in a tubular guide 25 contained wholly within the casing, while the sleeve containing the stem operates through the slot produced by the spaced front and back walls of the casing and is designed to engage in a series of concave recesses 26 formed in the edge portion of the flange 13 of the wall 11 so as to hold the stem in coincident relation radially outward with respect to indications 27 running from one to eighteen, or otherwise, depending upon the number of holes in the particular golf course. By this means, that is, due to the alinement of the stem with a particular number contained between the division lines 28 on the face of the register, the player is enabled to know which golf hole is being played. The sleeve carrying the stem is designed to frictionally engage with the inner edge of the flange or wall 13 so as to be held in one of the respective recesses.

30 The guide 25 is counter-bored to receive the stem 22, and a coiled spring 29, disposed between the inner end of the sleeve 22 and the end wall of the counterbore, is normally expanded to hold the sleeve and stem radially outward with respect to the casing. The inner end of the guide is also counter-bored to receive the reduced portion of a beveled pinion 30 normally in mesh with the beveled pinion 18 and rotatably supported in the counterbore by means of set screws 31 engaged in the peripheral groove 32 of the reduced sleeve portion of the beveled pinion 30, the guide being formed integrally with the bearing sleeve 19 so as to support said parts in the relation specified. The inner end of the stem is also squared, as shown at 33, to slidably engage a circular aperture in the sleeve of the guide 25 and a squared aperture in the beveled pinion 30 so that the latter will, upon rotation of the stem through the instrumentality of the knurled head by the fingers and independently of the sleeve 22, cause rotation of the pinions and cause a corresponding movement in a clockwise direction of a pointer 34 which is fixed to the beveled pinion 18 and which, after extending in a tortuous path to a point exteriorly of the casing through the slot between the front and back walls, is curved to overlie the face portion of the register. The pointer terminates adjacent to the divisional indication mark 35 running from one to one hundred and thirty and designed to indicate the grand total of strokes for the entire course by advancing the pointer after each stroke and after playing each hole, rotation of the stem imparting the desired movement of the pointer through the instrumentality of the intermeshed pinions for this purpose.

35 The front wall of the casing is provided between the indication marks 27 and 35 with a plurality of side openings 36 corresponding in number to the number of holes in the course, and said wall is further provided with spaced inwardly extending circular walls 37, the innermost of which extends as far as the edge of the wall 12 while the outermost circular wall terminates at a spaced distance from said edge. These circular walls are provided with pairs of aligned apertures disposed in the rear of the side openings 36 and designed to rotatably receive the stub shafts 38 of a plurality of indicating cylinders preferably numbered from one to twelve, shown at 40, to allow a wide margin for counting the number of strokes made for each hole. The outer edge of each cylinder is provided with beveled ratchet teeth 41, beveled in the direction in which the numbers progress, and the guide 25 is provided with a vertical slot 42 through which a projection 43 extends at right angles from the sleeve 22, said projection having a beveled lower edge designed to engage a tooth of one of the cylinders disposed in juxtaposition thereto so as to impart partial rotation to said cylinder to advance the same one numeral upon the sleeve being depressed through the instrumentality of the stem against the action of the coiled spring 29. This spring retains the sleeve and stem normally outward, the projection 43 engaging the end walls of the slot 42 to limit the movements thereof. Thus, the cylinders corresponding in number to the indications 27 disclosing the number of holes in the course may be partially rotated after each stroke, whereby when each hole is accomplished the cylinder will designate the total number of strokes made in playing a particular hole and the total of the numbers given on the cylinders will equal the grand total which will be shown by the pointer 34 on the indications or dials 35. If the total goes above 130, the counting is continued from zero and added on, but with fair playing this will not be necessary.

40 For convenience the counter may be suspended from a pocket or belt by means of a clasp-hook 44 carried by the back wall of the casing.

45 From the foregoing description in connection with the accompanying drawings, it will be obvious that the stem may be moved circumferentially in the slot between the front and back walls and owing to the fact that the bearing sleeve 19 freely rotates on the spacing sleeve 15, it is obvious that the pinion 30 will turn on the pinion 18 without

70 pointer after each stroke and after playing each hole, rotation of the stem imparting the desired movement of the pointer through the instrumentality of the intermeshed pinions for this purpose.

75 The front wall of the casing is provided between the indication marks 27 and 35 with a plurality of side openings 36 corresponding in number to the number of holes in the course, and said wall is further provided with spaced inwardly extending circular walls 37, the innermost of which extends as far as the edge of the wall 12 while the outermost circular wall terminates at a spaced distance from said edge. These circular walls are provided with pairs of aligned apertures disposed in the rear of the side openings 36 and designed to rotatably receive the stub shafts 38 of a plurality of indicating cylinders preferably numbered from one to twelve, shown at 40, to allow a wide margin for counting the number of strokes made for each hole.

80 The outer edge of each cylinder is provided with beveled ratchet teeth 41, beveled in the direction in which the numbers progress, and the guide 25 is provided with a vertical slot 42 through which a projection 43 extends at right angles from the sleeve 22, said projection having a beveled lower edge designed to engage a tooth of one of the cylinders disposed in juxtaposition thereto so as to impart partial rotation to said cylinder to advance the same one numeral upon the sleeve being depressed through the instrumentality of the stem against the action of the coiled spring 29.

85 This spring retains the sleeve and stem normally outward, the projection 43 engaging the end walls of the slot 42 to limit the movements thereof. Thus, the cylinders corresponding in number to the indications 27 disclosing the number of holes in the course may be partially rotated after each stroke, whereby when each hole is accomplished the cylinder will designate the total number of strokes made in playing a particular hole and the total of the numbers given on the cylinders will equal the grand total which will be shown by the pointer 34 on the indications or dials 35. If the total goes above 130, the counting is continued from zero and added on, but with fair playing this will not be necessary.

90 The outer edge of each cylinder is provided with beveled ratchet teeth 41, beveled in the direction in which the numbers progress, and the guide 25 is provided with a vertical slot 42 through which a projection 43 extends at right angles from the sleeve 22, said projection having a beveled lower edge designed to engage a tooth of one of the cylinders disposed in juxtaposition thereto so as to impart partial rotation to said cylinder to advance the same one numeral upon the sleeve being depressed through the instrumentality of the stem against the action of the coiled spring 29.

95 This spring retains the sleeve and stem normally outward, the projection 43 engaging the end walls of the slot 42 to limit the movements thereof. Thus, the cylinders corresponding in number to the indications 27 disclosing the number of holes in the course may be partially rotated after each stroke, whereby when each hole is accomplished the cylinder will designate the total number of strokes made in playing a particular hole and the total of the numbers given on the cylinders will equal the grand total which will be shown by the pointer 34 on the indications or dials 35. If the total goes above 130, the counting is continued from zero and added on, but with fair playing this will not be necessary.

100 The outer edge of each cylinder is provided with beveled ratchet teeth 41, beveled in the direction in which the numbers progress, and the guide 25 is provided with a vertical slot 42 through which a projection 43 extends at right angles from the sleeve 22, said projection having a beveled lower edge designed to engage a tooth of one of the cylinders disposed in juxtaposition thereto so as to impart partial rotation to said cylinder to advance the same one numeral upon the sleeve being depressed through the instrumentality of the stem against the action of the coiled spring 29.

105 This spring retains the sleeve and stem normally outward, the projection 43 engaging the end walls of the slot 42 to limit the movements thereof. Thus, the cylinders corresponding in number to the indications 27 disclosing the number of holes in the course may be partially rotated after each stroke, whereby when each hole is accomplished the cylinder will designate the total number of strokes made in playing a particular hole and the total of the numbers given on the cylinders will equal the grand total which will be shown by the pointer 34 on the indications or dials 35. If the total goes above 130, the counting is continued from zero and added on, but with fair playing this will not be necessary.

110 The outer edge of each cylinder is provided with beveled ratchet teeth 41, beveled in the direction in which the numbers progress, and the guide 25 is provided with a vertical slot 42 through which a projection 43 extends at right angles from the sleeve 22, said projection having a beveled lower edge designed to engage a tooth of one of the cylinders disposed in juxtaposition thereto so as to impart partial rotation to said cylinder to advance the same one numeral upon the sleeve being depressed through the instrumentality of the stem against the action of the coiled spring 29.

115 This spring retains the sleeve and stem normally outward, the projection 43 engaging the end walls of the slot 42 to limit the movements thereof. Thus, the cylinders corresponding in number to the indications 27 disclosing the number of holes in the course may be partially rotated after each stroke, whereby when each hole is accomplished the cylinder will designate the total number of strokes made in playing a particular hole and the total of the numbers given on the cylinders will equal the grand total which will be shown by the pointer 34 on the indications or dials 35. If the total goes above 130, the counting is continued from zero and added on, but with fair playing this will not be necessary.

120 For convenience the counter may be suspended from a pocket or belt by means of a clasp-hook 44 carried by the back wall of the casing.

125 From the foregoing description in connection with the accompanying drawings, it will be obvious that the stem may be moved circumferentially in the slot between the front and back walls and owing to the fact that the bearing sleeve 19 freely rotates on the spacing sleeve 15, it is obvious that the pinion 30 will turn on the pinion 18 without

5 imparting rotation to the latter. It will also be obvious that independent movement may be imparted to the stem and sleeve for the purpose of turning the cylinders irrespective of rotation of the pinions, but that by rotating the stem which is slidably keyed to the pinion 30, the pin 18 may be rotated to cause similar movement of the pointer therewith and by this means a perfect record of the 10 game may be had at all times. It is also obvious that the means herein described for registering which golf hole is being played, the number of strokes made for each hole and the grand total of strokes, is simply 15 illustrative of one embodiment, although especial advantage is derived in causing the stem to control the three operations providing for the keeping of such registration.

Having thus described my invention, what 20 I claim as new and desire to secure by Letters Patent is:—

1. In a pocket golf register, the combination with a casing having a face portion with indications designating the number of 25 holes to be played and numbers indicating the grand total of strokes; of a stem carried by the casing, a pointer movably carried by the casing and coöperating with the last-mentioned indications and oper- 30 atively connected to the stem, said stem to be moved thereby coöperating with the first-mentioned indications, a plurality of movable cylindrical dials carried by the cas- 35 ing and journaled at right angles to the axis thereof, and means for stepping said dials by means of the stem to indicate the number of strokes for each hole.

2. In a meter for golf scores, a casing embodying front and back walls spaced apart, 40 the face portion of the casing having indications designating the number of holes in a course and a dial designed to permit a registration of the total number of strokes in the course, a plurality of cylinders each 45 rotatably supported with their base parallel with the axis of the casing and visible through the casing, said cylinders having indications thereon from 1 to 12 inclusive, a stem movable between the walls of the 50 casing and rotatably supported at the center of the latter, a pointer coöperating with the dial and geared to the stem whereby it may be shifted, said stem being adapted for inward movement, and coöperating 55 means carried by the cylinders and stem for causing partial rotation of a cylinder disposed in juxtaposition thereto for advancing the same one unit and simultaneously indicating the number of strokes 60 for each hole, said stem coöperating with the first-named indications to designate the hole being played.

3. In a register for keeping golf scores, a circular casing including front and back 65 walls having edge portions, means connect-

ing said walls in spaced relation, the edge of one of said walls having spaced recesses, a pinion snugly fitted on said connecting means to rotate, a guide having a sleeve portion loosely mounted on said connecting 70 means, a pinion rotatably carried by said guide and disposed in mesh with the first-named pinion, a sleeve slidably engaged with said guide and designed to spring into said recesses and held against movement 75 with respect to the casing, a stem carried by the sleeve for independent rotation and simultaneous sliding movement, said stem being keyed to the second-named pinion whereby rotation may be imparted to the 80 first-named pinion, a pointer carried by the last-named pinion and movable over one face of the casing, a dial coöperating with said pointer to designate the grand total of strokes, said front wall having spaced 85 flanges with communicating openings, cylinders rotatably journaled in said flanges at spaced points adjacent to the openings and having numbers thereon, one edge wall of each cylinder having beveled teeth, a 90 projection carried by the sleeve and coöperating with said teeth to cause partial rotation of a cylinder disposed adjacent thereto upon inward displacement of the stem to indicate the number of strokes for 95 each hole, and means normally holding said stem and sleeve outward and the projection spaced from the adjacent cylinder.

4. In a register for keeping golf scores, a circular casing including front and back 100 walls having edge portions, means connecting said walls in spaced relation, the edge of one of said walls having spaced recesses, a pinion snugly fitted on said connecting means to rotate, a guide having a sleeve portion loosely mounted on said connecting 105 means, a pinion rotatably carried by said guide and disposed in mesh with the first-named pinion, a sleeve slidably engaged with said guide and designed to spring into said 110 recesses and held against movement with respect to the casing, a stem carried by the sleeve for independent rotation and simultaneous sliding movement, said stem being keyed to the second-named pinion whereby 115 rotation may be imparted to the first-named pinion, a pointer carried by the last-named pinion and movable over one face of the casing, a dial coöperating with said pointer to designate the grand total of strokes, said front wall having spaced flanges with communicating 120 openings, cylinders rotatably journaled in said flanges at spaced points adjacent to the openings and having numbers thereon, one edge wall of each cylinder 125 having beveled teeth, and a projection carried by the sleeve and coöperating with said teeth to cause partial rotation of a cylinder disposed adjacent thereto upon inward displacement of the stem to indicate the num- 130

ber of strokes for each hole, there being indications on one face of the casing designating the number of holes in the course, said stem and sleeve coöperating with said 5 indications alined with respect to the recesses to indicate the hole being played.

In testimony whereof I have signed my

name to this specification in the presence of two subscribing witsesses.
